UNITED STATES PATENT OFFICE

JOSEPH SUNNEN, OF ST. LOUIS, MISSOURI

SPLIT-LOCK REPLACER

Application filed July 8, 1929. Serial No. 376,573.

This invention relates generally to tools for internal combustion engines and more particularly to split lock replacers.

In the valve assembly of most internal combustion engines, the valve is held to its seat by means of a coiled spring, one end of which rests against a part of the engine block, while the other end bears against a retaining washer which is mounted on the stem of the valve. Generally this washer is locked in position on the stem by a split lock comprising a pair of longitudinal halves having their outer faces tapered upwardly and adapted to be received in a peripheral groove formed in said valve stem, near the lower end thereof. This split lock, when arranged in said groove, fits into an upwardly tapered seat formed in the underside of said washer. Thus said washer serves to retain the lock members in operative position and the latter hold the washer on the stem.

In the assemblage of the valve structure, and particularly in the replacement of the split lock members, a great deal of difficulty is experienced in maintaining said split lock members in proper position, while the valve spring is being released. This troublesome condition is partly due to the limited space in which the work is done and partly to the peculiar construction of the valve assembly.

It is the purpose of the present invention to provide a split lock replacer by means of which the split lock members can be replaced with ease in a short period of time and which replacer is so constructed that it will hold the split lock members in proper position during the release of the valve spring and will automatically become disengaged from said split lock members as the latter are engaged by the retaining washer.

Further objects of the invention are to provide a split lock replacer having cooperating yielding arms for receiving and holding the split lock members during the replacement thereof, said arms being yieldable to release said lock members when the latter are engaged by the retaining washer.

Still further objects of the invention are to provide a pair of cooperating yieldable arms having a tapered seat for receiving the split

lock members in proper relation, and to provide a member cooperating with said arms and movable relatively to said seat for locking said split lock members in position in said seat, and to provide a handle by means of which said replacer can be manipulated.

With these and other objects in view, my invention consists in certain novel features of construction and arrangement of parts, hereinafter more fully described and claimed, and illustrated in the accompanying drawings, in which—

Figure 1 is a side elevational view of the replacer, shown applied to the valve assembly.

Figure 2 is a top plan view of the same.

Figure 3 is an enlarged cross section taken on line 3—3 of Figure 1.

Figure 4 is a view similar to Figure 1 but showing the tool being disengaged from the lock members.

Figure 5 is a top plan view of the bifurcated end of the retainer member.

Referring by numerals to the accompanying drawings, 10 indicates a holder consisting of a pair of parallel arms 11, the outer end portions 12 of which are shaped to form an open-ended upwardly tapering seat 14. The general dimensions of this seat or recess are such as to receive freely the two halves forming the split lock A. These arms are formed yieldable and their extreme ends 12^a are flared outwardly so as to facilitate the engagement and disengagement of said arms with the split lock members.

A retainer member or lock 15 is pivotally mounted at one end between said arms 11 by means of a horizontally and transversely disposed pin 16, the ends of which are seated in said arms 11. As shown in the drawings, this retainer member 15 extends downwardly below arms 11 and then forwardly and terminates in a bifurcated end 17 which is disposed immediately below the lower flared-out end of recess or seat 14, and preferably coaxial therewith. This bifurcated end 17 is so shaped as to fit snugly within the lower end of said seat and hold the split lock members thereto. The opening or notch formed by said bifurcated end is large enough to clear freely the lower end of valve stem B.

The intermediate portion 15^a of said retainer member is disposed horizontally, preferably below the horizontal planes of both ends. A handle 18 has one end connected to this intermediate portion, preferably pivotally, by means of a pin 19, and said handle extends rearwardly therefrom in a direction opposite to the bifurcated end 17. This handle is of sufficient length to enable the user to manipulate the device in a convenient manner and is pivotally connected to the lock member or retainer 15 so that the replacer can be set at an angle to the longitudinal axis of said handle.

15 Thus the ends 12 of the arms 11 form an open-ended frustro conical seat into which the split lock members are inserted. In placing the lock members in position therein, the holder is inverted to bring the large end of the seat upwardly and the lock members are dropped therein. The retainer 15 is now moved so as to bring the bifurcated end 17 against said lock member. This retainer prevents the lock members from dropping out when the tool is righted. The tool is inserted in position so as to bring said lock members below the lower end of the valve stem whereupon the latter is inserted through the opening formed by said lock members. As the 30 arms 11 are yieldable, they prevent separation of the split lock member during the insertion of the lower end of the stem and return it to normal or closed position and seat said lock members in the groove of the stem 35 as soon as said groove is in position.

My improved replacer is of simple construction, is efficient in performing its intended functions, and is easily manufactured.

40 While I have shown and described herein the preferred form of my invention, it is obvious that various changes in the construction and arrangement of parts of my replacer can be made and substituted for those herein shown without departing from the spirit of my invention.

I claim:

1. A split lock replacer comprising a handle, a retainer member disposed above said handle and secured to one end thereof, and a pair of yieldable arms arranged above said retainer member and pivotally carried thereby, the ends of said arms being shaped to receive the split lock members of a valve assembly, 55 said arms and said retainer member being pivotally movable relatively to each other to allow insertion of said lock members between the yieldable ends of said arms and to retain said lock members therein, said arms being yieldable so as to become disengaged from said lock members when the latter are engaged by the valve stem.

60 2. A split lock replacer comprising a handle, a U-shaped resilient member, the ends of which are shaped to form an upwardly ta-

pering recess, and a retainer member pivotally mounted at one end to said U-shaped member for pivotal movement toward and from the plane thereof, the free end of said retainer member being arranged to cooperate 70 with said ends for closing the large end of said recess and retain the lock members in position therein.

3. A split lock replacer comprising a pair of yieldable arms having their free ends shaped to form an upwardly tapering recess for receiving split lock members, and a retaining member pivotally mounted between said arms to move toward and from the plane thereof, said retaining member having a bifurcated end movable adjacent to the lower end of said recess for retaining the split lock members therein. 75

4. A split lock replacer comprising a holder having yieldable portions shaped to form a vertically disposed upwardly tapering open-ended seat for receiving the split lock members, and a retaining member pivotally mounted at one end to said holder for movement toward and from the plane thereof, thereby cooperating with the lower end of said seat and retaining said split lock members therein. 80

5. A split lock replacer comprising a holder having yieldable portions shaped to form a vertically disposed open-ended seat for receiving the split lock members, a retaining member pivotally mounted at one end to said holder for movement toward and from the plane thereof, thereby providing a bottom 100 for said seat, and retaining said split lock members therein, the end of said retaining member forming the bottom for said seat being slotted to provide clearance for the valve stem, and a handle secured to said retaining member and extending therefrom in a direction opposite to said bifurcated end. 105

6. A split lock replacer comprising a member having a pair of laterally yieldable arms, the ends of which are provided with oppositely disposed semi-circular recesses tapering upwardly and cooperating to receive the split lock members, and a retaining member pivotally mounted between said arms and swingable at right angle thereto, the free end 115 of said member having a bifurcated end movable adjacent to the lower ends of said recessed arm so as to form a bottom for said recessed ends and hold said split lock members in position therein. 120

7. A split lock replacer comprising a member having a pair of yieldable arms, the ends of which are provided with oppositely disposed semi-circular recesses tapering upwardly and cooperating to receive the split lock members, a retaining member mounted for movement toward and from the plane of said arms, said retaining member having a bifurcated end positionable adjacent to said recessed ends so as to close the lower end of 125 130

the tapered seat formed thereby and retain said split lock members in position, and a handle fixed at one end to said retaining member and extending therefrom in a direction opposite to the bifurcated end thereof.

8. In a device of the class described, a split lock replacer for valve stems comprising in combination a U-shaped resilient member, the ends of which are provided with oppositely disposed semi-circular recesses tapering upwardly and cooperating to receive the split lock members, said ends being yieldable to release said lock members when said U-shaped member is withdrawn from the valve stem, and means movable into engagement with the lower portions of said tapered ends for closing the lower ends of said recesses and retaining said lock members in position.

9. In a device of the class described, a split lock replacer for valve stems comprising a U-shaped resilient member, the ends of which are provided with oppositely disposed semi-circular recesses tapering upwardly and cooperating to receive the split lock members, said ends being yieldable to release said lock members when said U-shaped member is withdrawn from the valve stem, a retaining member operatively mounted on said resilient member and having one end enlarged to form a circular portion provided with a radial slot, said retaining member being operable to bring said enlarged end into engagement with the lower portions of said tapered ends for retaining said lock members in position, and a handle extending rearwardly from said retaining member for manipulating said lock replacer.

In testimony whereof I hereunto affix my signature this 29 day of June, 1929.

JOSEPH SUNNEN.
